UNITED STATES PATENT OFFICE.

CHARLES ADELHELM, OF CHICAGO, ILLINOIS, ASSIGNOR TO HIMSELF AND PATRICK T. HARMON, OF CHICAGO, ILLINOIS.

AMUSEMENT DEVICE.

No. 899,497.

Specification of Letters Patent.

Patented Sept. 29, 1908.

Application filed September 7, 1907. Serial No. 391,808.

To all whom it may concern:

Be it known that I, CHARLES ADELHELM, a citizen of the United States, residing at Chicago, in the county of Cook and State of Illinois, have invented certain new and useful Improvements in Amusement Devices; and I do hereby declare the following to be a full, clear, and exact description of the invention, such as will enable others skilled in the art 10 to which it appertains to make and use the same.

My invention relates to a novel construction in a device of the so-called "merry-go-round" type, the object being to provide an 15 amusement device of this character by means of which passengers are given a variety of sensations tending to increase the entertainment afforded, and consists in the features of construction and combinations of parts hereinafter fully described and claimed.

In the accompanying drawings illustrating this invention: Figure —1— is a top plan view of my device. Fig. —2— is a top plan view of the frame work supporting the revolving platform, and showing the operating mechanism. Fig. —3— is a fragmentary central vertical section on an enlarged scale on the line 3—3 of Fig. —2—. Fig. —4— is a vertical transverse section on the line 4—4 of Fig. —2—. Fig. —5— is a fragmentary plan view showing the rocking beam and operating mechanism actuating the same on which the passenger carrying platforms are disposed. Fig. —6— is a detail vertical section on the line 6—6 of Fig. —4—, showing the manner of supporting step bearings employed. Fig. —7— is a detail plan section showing the same.

My said invention consists essentially in 40 providing a main revolving frame carrying a main platform and a plurality of smaller platforms which are rotated independently of the main platform and relatively thereto, while at the same time they are reciprocated vertically, the passengers carried by said smaller platforms thus subjected to a complexity of movement which is very sensational and affords the highest degree of entertainment, the complex movement forming the main object of the invention.

Other objects of the invention are to render the mechanism employed very simple and efficient to maintain repairs at a minimum, and to render the device very simple

and safe in every respect to avoid possibility 55 of accidents to passengers.

My said device comprises a rectangular frame 1 constructed in a manner to afford the necessary strength, the details of such construction forming no part of the invention. 60 The said frame is supported in any suitable manner on car-wheels 2 traveling on the circular track 3 supported on the ground.

Centrally of the circular track is a suitable block 4 preferably disposed in a well in the 65 ground and suitably held against rotation, and on which a horizontally disposed bevel gear 5 is rigidly mounted.

The frame 1 carries the motor 6 preferably electric, to which the current is applied in 70 any suitable manner illustration of which is omitted. Said motor actuates the drive shaft 7 geared at one end to said bevel gear 5 by means of the bevel pinion 8, whereby said frame 1 is rotated as will be obvious. 75 Pivotally mounted upon said frame 1 midway between their ends and at diametrically opposite points, are the rocking or oscillating points 9 to the free ends of which step-bearings 10 are pivotally hung by means of 80 links 11, said step-bearings being provided with central openings through which the vertical shafts 12 pass. The latter support the passenger platforms 13 at their upper ends and between their ends carry rigid 85 collars 14 which are adapted to rest upon the upper faces of said step-bearings 10, anti-friction devices such as balls 15 being interposed between the same. The said vertical shafts 12 are rotatable in bearings 16 90 supported on the frame 1 or the platform 17 carried by the latter, and are also vertically movable in said bearings, the lower ends of said shafts 12 passing through the hubs of bevel gears 18 rotatably disposed on the 95 frame 1 and are vertically movable in the latter but maintained against rotation relatively thereto in any suitable manner. The said shafts 12 are rotated relatively to the frame 1 by means of countershafts 19 carrying bevel pinions 20 and 21 at their ends which mesh with said bevel gears 5 and 18 respectively. The said beams 9 consist of two parallel bars each which are reinforced by means of tension bars 22 in a well known 100 manner.

To the frame 1 hangers 23 are mounted and to the lower end of each of the same a

lever 24 is pivotally secured at one end, the other end thereof being connected by means of the link 25 with one of the rocking beams 9 between the pivot and one of the free ends thereof. Between said ends said lever 23 is provided with a lateral projection 26 which enters the peripheral distorted groove in a cam 27 disposed on a shaft 28 journaled in bearings 29 and 30 on said frame 1, and 10 rigid with which is a spur gear 31. The latter meshes with a spur pinion 32 on a vertical shaft 33 carrying the bevel gear 34 which meshes with the pinion 35 on the drive-shaft 7 or the countershaft 36 which 15 is geared to said drive-shaft through the intermediary of the bevel gear 5.

From the foregoing it will be readily seen that the motor 6 causes the frame 1 to rotate, and through the intermediary of the above 20 described gearing also rotates the platforms 13 and also the cams 27 thereby causing the beams 9 to oscillate and thus vertically reciprocate said platforms 13 while the same are rotating. It will be further noted that 25 the platforms 13 rotate relatively to the frame 1 in the same direction as the latter which produces the same effect as varying the speed of rotation of said platforms during each revolution, for the reason that the 30 peripheral speed of the same is added to the speed of the frame 1 as any point in the periphery of said platforms 13 approaches the point farthest removed from the axis of rotation of said frame 1, while the contrary 35 is true as it approaches the axis of the latter, hence, the whirling at variable speed added to the vertical movement is productive of very unique sensations which are intensely fascinating and amusing. The said platforms 40 13 carry seats 37 preferably disposed radially so that the passengers face in the direction of movement.

The main platform is equipped with stairways 38 to enable the same to be easily 45 mounted.

A suitable covering may be provided over the device and the latter properly guarded by railways to prevent accidents.

I claim as my invention:

50 1. A device of the kind specified comprising a frame revolvably supported on a circular track, a motor rotating the same, a walking beam pivotally supported on said frame, a cam actuated by said motor and operatively 55 engaging said walking beam to rock the same, bearings supported upon the end portions of said walking beam, platforms disposed on vertical shafts supported by said bearings and driving gear actuated by said 60 motor and rotating said shafts.

2. A device of the kind specified comprising a frame revolvably supported on a circular track, a motor rotating the same, a walking beam pivotally supported on said frame, a 65 cam actuated by said motor and operatively

engaging said walking beam to rock the same, bearings pivotally supported upon the end portions of said walking beam, platforms disposed on vertical shafts passing through said bearings, collars on said shafts 70 between their ends and bearing upon the upper faces of said bearings to support said platforms, and drive-gear disposed in operative relation to said shafts and said motor to transmit rotary movement to the former. 75

3. A device of the kind specified comprising a frame revolvably supported on a circular track, a motor rotating the same, a walking beam pivotally supported on said frame, a cam actuated by said motor and operatively 80 engaging said walking beam to rock the same, parallel depending links pivotally secured to the ends of said walking beam, vertical sleeves pivotally secured between their ends to the lower ends of said links, revoluble 85 platforms disposed on vertical shafts passing through said sleeves, collars disposed upon the said vertical shafts between their ends and engaging said sleeves to support said platforms, anti-friction devices interposed 90 between said collars and said sleeves, and drive-gear disposed in operative relation to said vertical shafts and said motor to impart rotary movement to the former.

4. A device of the kind specified comprising a main rotating frame equipped at diametrically opposite points with walking beams, a motor actuating said platform, means actuated by said motor and rocking said walking beams, passenger carriers disposed on vertical shafts rotatably mounted upon the free ends of said walking beams and adapted to be vertically reciprocated by the latter, means maintaining said shafts vertical, and drive gear disposed in operative relation to said shafts and said motor to rotate 100 the former.

5. A device of the kind specified comprising a main rotating frame equipped at diametrically opposite points with walking 110 beams, a motor actuating said platform, means actuated by said motor and rocking said walking beams, passenger carriers disposed on vertical shafts rotatably mounted upon the free ends of said walking beams and adapted to be vertically reciprocated by the latter, means maintaining said shafts vertical, and drive gear disposed in operative relation to said shafts and said motor to rotate 115 the former, said means actuating said walking beams being disposed to impart respectively opposite movement to the latter.

In testimony whereof I have signed my name in the presence of two subscribing witnesses.

CHARLES ADELHELM.
